UNITED STATES PATENT OFFICE.

FANNIE L. DE GRAFF, OF PORTLAND, OREGON.

GARMENT-SUPPORTER.

No. 851,923.

Specification of Letters Patent.

Patented April 30, 1907.

Application filed October 30, 1906. Serial No. 341,351.

To all whom it may concern:

Be it known that I, FANNIE L. DE GRAFF, a citizen of the United States, residing at Portland, in the county of Multnomah and State of Oregon, have invented new and useful Improvements in Garment-Supporters, of which the following is a specification.

This invention is a garment-supporter, and has for its object to provide an improved device for connecting a skirt and waist so that the weight of the former will be borne by the shoulders and not by the hips.

A further object is to provide a supporter which can be readily attached and which will hold the garments in proper position without drawing the waist-bands of the garments tightly around the hip.

In the accompanying drawing, Figure 1 is a perspective view of the belt. Fig. 2 is an elevation of a portion thereof. Figs. 3, 4 and 5 are sectional views on the lines 3, 4 and 5, respectively, of Fig. 2 showing the application of the invention.

Referring specifically to the drawing, 10 denotes a belt which is made of suitable elastic material. To one end of the belt is sewed or otherwise secured an inelastic strip 11 provided at its end with a hook 12. The other end of the belt is provided with a similar strip 13 having an eye 14 to receive the hook 12, whereby the belt is secured to the waist of the wearer. Any other suitable fastening means may be employed.

To the belt 10 are sewed or otherwise secured a number of spaced strips 15 of suitable inelastic material, and where these strips occur, are secured the pins which fasten the garments to the belt. These pins are specially constructed and are presented on both sides of the belt, those on the inner side being intended to engage the waist and under-waist, and the ones on the outer side of the skirt and under-skirt.

The pins on the inner side of the belt comprise an attaching shank 16 which is secured to the belt 10 and the strip 15 by forming loops in the shank and extending the loops through the belt and strip. The shank is thus fastened to the belt and strip at their upper and lower edges as at 17 and 18, and also at or about the middle as at 19. The pin proper is indicated at 20 and is downwardly presented from the loop 17. At the lower edge of the belt the shank 16 is formed

with a guard 21 which receives the point of 55 the pin. The loop 17 renders the pin resili-ent where it is retained in the guard.

Two different kinds of pins 22 and 23, re-spectively, are employed for the outer side of the belt. The pins 22 are in all respects 60 similar to the ones on the inner side of the belt, with the exception that they are pre-sented in the opposite direction or upwardly. The pin 23 is also upwardly presented. Its shank 24 extends across the inner surface of 65 the belt, and is looped as at 25 and 26 through the belt 10 and strip 15 at its upper and lower edges, respectively. From the loop 26 the shank extends across the outer surface of the strip 15 and at or about the 70 middle thereof it is looped through the strip and belt as at 27 from which loop the pin ex-tends. A guard 28 for the point of the pin is also provided.

In use, the shirt waist 29 and under-waist 75 or other garment 30 are fastened by the pins 20 on the inner side of the belt. The under-skirt 31 is fastened by the pins 22 and the outer skirt 32 by the pins 23. As the latter pins are situated above the former, the outer 80 skirt will be supported above the under-skirt, whereby the garments are made to present a neat appearance. By spacing the pins 22 and 23 they are extended through one garment only so that the supporter can 85 be quickly and easily put on. This arrange-ment is especially advantageous when heavy garments are worn in view of the difficulty that would be experienced in inserting the pins, and also the pins in supporting the gar-ments.

The supporter holds the garments together evenly without necessitating the drawing of the waist bands tightly around the hips, and the belt can be left loose on the waist. It 95 will keep straight on the waist line and trans-fer the strain and pull on the garments from the hips to the shoulders. As the belt is elastic it will give when the wearer stoops or bends, and the strips 15 prevent the pins 100 from tearing out.

The front of the belt can also be provided with pins, as indicated at 33 for dip-waists and for holding the dress-belt 34 in proper position.

I claim:

A garment-supporter comprising a belt carrying a series of pins having their attach-

ing shanks located on one side of the belt, and looped at their ends through the belt adjacent its upper and lower edges, respectively; a pin on the opposite side of the belt 5 extending from one of the loops; and a guard on the other loop to receive the point of the pin.

In testimony whereof I have signed my name to this specification in the presence of two subscribing witnesses.

FANNIE L. DE GRAFF.
